ROLLING MILL

Charles W. Phillips, Warren, Ohio

Application September 3, 1935, Serial No. 39,002

6 Claims. (Cl. 80—38)

The invention relates to rolling mills and more especially to cold metal strip rolling mills.

The primary object of the invention is the provision of a mill of this character, wherein the rolls for action upon a metal strip for the cold rolling of the same are supported in a novel manner so that the position thereof can be shifted and in this fashion assuring throughout the operation of the mill a smooth and flat action on the strip and in this way avoiding the grooving of these rolls with the result that the material acted upon can be drawn out to reduce thickness of the strip and to assure a smooth finish thereto.

Another object of the invention is the provision of a mill of this character, wherein the rolls supported for adjustment transversely of the mill housings are shifted through gear and rack connections in a novel manner and in this fashion a uniformity of wear upon these rolls is assured with the result that the strip acted upon will be smooth and at the same time avoiding the possibility of pitting or uneven wearing of the same during the operation of the mill.

A further object of the invention is the provision of a mill of this character, wherein the work to be operated upon can be readily handled and such work reduced and finished in strip form and at the same time accomplishing this efficiently and economically, the rolls acting upon the work being so mounted for adjustment for altering the working surface thereof in confronting relation to the work.

A still further object of the invention is the provision of a mill of this character, wherein the rolls operating upon the work are so held as to have little or no tendency to vibrate for producing "chatter" marks on the surface of the rolled strip.

A still further object of the invention is the provision of a mill of this character, which is simple in its construction, thoroughly reliable and efficient in its operation, durable and inexpensive to manufacture.

With these and other objects in view, the invention consists in the features of construction, combination and arrangement of parts as will be hereinafter more fully described, illustrated in the accompanying drawings, which disclose the preferred embodiment of the invention and pointed out in the claims hereunto appended.

In the accompanying drawings:

Figure 1 is an elevation of a mill constructed in accordance with the invention.

Figure 2 is a top plan view partly broken away. Figure 3 is an end elevation.

Figure 4 is a fragmentary enlarged sectional view taken on the line 4—4 of Figure 2 looking in the direction of the arrows.

Figure 5 is a sectional view on the line 5—5 of Figure 1 looking in the direction of the arrows.

Figure 6 is a sectional view on the line 6—6 of Figure 1 looking in the direction of the arrows.

Similar reference characters indicate corresponding parts throughout the several views in the drawings.

Referring to the drawings in detail, the mill comprises a pair of spaced vertical mill housings 10 and 11, respectively, these vertically arranged in their spaced relation to each other and are joined together by cross tie bars or rods 12 made secure in the housings in any suitable manner. The lower ends of these housings 10 and 11 are provided with feet 13 to rest upon a foundation or flooring and arranged at the outer sides of such housings are laterally disposed stands or tables 14 for a purpose presently described.

The housings 10 and 11 are formed with windows 15 accommodating bearings 16 and 17, respectively, these accommodating the necks of backing-up rolls 18 between which are located the working rolls 19. The rolls 19 have their tapered necks fitting bearings 20 in their superposed relation to each other. The bearings 20 are fitted in boxings 21 which are fixed to and carried by conveyors 22 so that the rolls 19 in their parallel relation to each other can be shifted as a unit crosswise of the housings 10 and 11 between the rolls 18 which are above and below the said rolls 19.

The conveyors 22 have trackage at 23 in the tables or stands 14 and are arranged in a horizontal plane.

Each conveyor 22 is formed with a toothed rack 24 meshing with a rack pinion 25 having its arbor 26 journaled in the side walls of each of said tables or stands 14. The arbor 26 at one side of the table 14 carrying the same extends therefrom and has a flat faced terminal 27 for fitting with a turning crank (not shown) so that each conveyor can be shifted for changing the position of the working rolls 19 with respect to the work.

The manner of mounting the backing-up rolls 18 above the working rolls 19 is shown in Figure 6 of the drawings. There the bearings 17 are shown normally urged apart by means of suitable

coiled springs 28. The bearings 20 for the rolls 19 are slidably fitted in the boxings 21.

The screw-down mechanism involves the vertical screws 29, these threaded in the upper cap ends 30 of the housings 10 and 11 and the inner ends of these screws 29 play against the bearings 17 on those sections uppermost with relation to the springs 28 and such screws 29 are manually regulated for screw-down action.

10 The windows 15 at opposite sides of the housings are closed by sectional removable cover plates 31 which have clearances 32 and 33 for the uppermost of the rolls 18 and the working rolls 19, respectively.

15 The steel strip, a portion being indicated at 34, is passed between the rolls 18 and over guide rolls 35 suitably journaled in the housings 10 and 11 at opposite sides of the vertically arranged rolls 18 and 19 and this strip 34 is wound on and unwound from feed drums (not shown) they being of conventional form and in the operation of the mill the strip is reciprocated by the alternate winding and unwinding of said strip by the drums which are driven in any desirable manner through an electric motor (not shown).

20 It is preferable to have each table 14 formed with an opening 36 located at the rack gear pinion 25 so that it can be removed when the occasion requires and especially through the bottom of the table without necessitating the detachment of the conveyor having trackage with in this table.

25 The bearings 20 fitting the boxings 21 are susceptible of separation accordingly to the requirements of the reduction of thickness of the strip 34 and such adjustment is had in that each boxing includes a capping part 37 held down by tensioning means 38.

30 On reciprocating the work, that is to say, the strip 34 the same is subjected to a drawing action or high tension and also to compression suitable for reducing the thickness of the metal of the strip, the compression being effected by the rolls 19 which frictionally operate and coact with the rolls 18.

35 It will be apparent from Figure 4 of the drawings that these working rolls 19 are susceptible of adjustment transversely of the housings 10 and 11 between the rolls 18 and the compression is regulated by the screw-down mechanism in the operation of the mill.

The strip 34 is cold rolled in the mill when the same is operated.

40 What is claimed is:

1. In a mill of the character described comprising backing-up rolls, superposed working rolls between said backing-up rolls and parallel therewith, the working rolls being of considerably greater length than the backing-up rolls and constantly between the latter, conveyors carrying said working rolls, and means for shifting the conveyors to move the working rolls axially with relation to the backing-up rolls and a distance approximately one-half the length of said backing-up rolls.

45 2. In a mill of the character described comprising backing-up rolls, superposed working rolls between said backing-up rolls and parallel therewith, the working rolls being of considerably greater length than the backing-up rolls and constantly between the latter, conveyors carrying said working rolls, means for shifting the

5 conveyors to move the working rolls axially with relation to the backing-up rolls and a distance approximately one-half the length of said backing-up rolls, and means for vertical adjustment of one of the working rolls.

50 3. In a mill of the character described comprising backing-up rolls, superposed working rolls between said backing-up rolls and parallel therewith, the working rolls being of considerably greater length than the backing-up rolls and constantly between the latter, conveyors carrying said working rolls, means for shifting the conveyors to move the working rolls axially with relation to the backing-up rolls and a distance approximately one-half the length of said backing-up rolls, means for vertical adjustment of one of the working rolls, and a screw-down mechanism operating on the uppermost backing-up roll.

55 4. In a mill of the character described comprising backing-up rolls, superposed working rolls between said backing-up rolls and parallel therewith, the working rolls being of considerably greater length than the backing-up rolls and constantly between the latter, conveyors carrying said working rolls, means for shifting the conveyors to move the working rolls axially with relation to the backing-up rolls and a distance approximately one-half the length of said backing-up rolls, means for vertical adjustment of one of the working rolls, a screw-down mechanism operating on the uppermost backing-up roll, and guide rolls at opposite sides of the working rolls for guiding strip material therebetween.

60 5. In a mill of the character described comprising backing-up rolls, superposed working rolls between said backing-up rolls and parallel therewith, the working rolls being of considerably greater length than the backing-up rolls and constantly between the latter, conveyors carrying said working rolls, means for shifting the conveyors to move the working rolls axially with relation to the backing-up rolls and a distance approximately one-half the length of said backing-up rolls, means for vertical adjustment of one of the working rolls, a screw-down mechanism operating on the uppermost backing-up roll, guide rolls at opposite sides of the working rolls for guiding strip material therebetween, and mill housings arranged in vertical spaced relation to each other and supporting the backing-up rolls.

65 6. In a mill of the character described comprising backing-up rolls, superposed working rolls between said backing-up rolls and parallel therewith, the working rolls being of considerably greater length than the backing-up rolls and constantly between the latter, conveyors carrying said working rolls, means for shifting the conveyors to move the working rolls axially with relation to the backing-up rolls and a distance approximately one-half the length of said backing-up rolls, means for vertical adjustment of one of the working rolls, a screw-down mechanism operating on the uppermost backing-up roll, guide rolls at opposite sides of the working rolls for guiding strip material therebetween, mill housings arranged in vertical spaced relation to each other and supporting the backing-up rolls, and stands associated with said housings and having trackage for the conveyors.
